CLARENCE S. HOWELL, OF NEW YORK, N. Y., ASSIGNOR, BY MESNE ASSIGNMENTS, OF ONE-HALF TO LAWRENCE McGUIRE, OF NEW YORK, N. Y.

CONCRETE PILE CONSTRUCTION.

1,352,128.

Specification of Letters Patent. Patented Sept. 7, 1920.

Application filed September 1, 1915. Serial No. 48,533.

To all whom it may concern:

Be it known that I, CLARENCE S. HOWELL, a citizen of the United States, and a resident of the city, county, and State of New York, 5 have invented certain new and useful Improvements in Concrete Pile Construction, of which the following is a specification.

My invention relates to a concrete pile and a form for driving it. The device is 10 intended to make possible the adoption of a new method of concrete pile construction and the method will be more or less referred to in the description of the device, but the method will not be claimed herein 15 as it forms the subject matter of my copending application filed concurrently herewith and serially numbered 48,532.

My invention relates to the construction 20 of concrete piles and their driving means. Heretofore, two general methods for pile construction have been in use, viz: that by which concrete is cast in the shape of a pile in a form temporarily driven to the required depth in the ground, and that by 25 which a pile is cast above ground and seasoned and then driven to the required depth by one of several methods of driving. My invention relates to the latter class. Each of the prior methods of driving have certain 30 inherent disadvantages which are eliminated by the present invention. With the present invention a pile can be driven without defect and to great depths without fracture because injurious compression blows are not 35 applied to the pile. Other advantages of the present invention are: The concrete pile is made to occupy the displacement of the driving point as penetration proceeds by stresses applied through reinforcing bars 40 rigidly anchored to the point.

The pile may be of any cross-sectional shape and the advantages herein set forth 45 may nevertheless be attained. The pile is driven by means of a metal driving form of a plurality of sections or parts, preferably of channel shape, which do not entirely inclose the pile, so that there is some earth friction upon the pile. This partial earth friction on the pile develops a resistance to penetration which resistance is overcome by the reinforcing rods on which tensile stresses act. These stresses are distributed throughout the pile instead of acting 50 only at the point.

Another advantage of the partial earth

friction on the pile is that the pile is not moved upwardly from any given position of penetration by the upward pull of the driving forms during driving, nor is the pile displaced by the withdrawal of the 60 driving form.

By making the driving form in sections there is less earth friction when the parts are withdrawn separately, and the pile may be placed between the driving form members 65 easily preparatory to driving. Since the earth friction upon the withdrawal of the form members is less than it would be if a single form member inclosing the whole pile were used, a pile may be driven deeper 70 and still the form may be readily withdrawn thereafter.

The stress on the reinforcing rods may be so proportioned as not to exceed their elastic limit.

Cushioning devices on the driving head are not required to protect the pile from fracture by the driving force, so that the full force of the driver may be used for 80 rapid penetration.

In the drawings forming part of this application,

Figure 1 is an elevation of the pile and driving form in position between the leads of a pile driver, ready to be driven,

Fig. 2 is a vertical sectional view of the pile point, the concrete being omitted to show more clearly the other parts,

Fig. 3 is a vertical sectional view of the pointed end of the pile after the pile has 90 been driven and the driving form has been removed, in which view, part of the concrete, *i. e.* that on one half, has been omitted to better show the construction,

Fig. 4 is a sectional view taken on the line 95 4-4 of Fig. 3, with the same omission of concrete,

Fig. 5 is a horizontal sectional view through the driving head and it is taken on the line 5-5 of Fig. 6,

Fig. 6 is a vertical sectional view of the driving head and it is taken on the line 6-6 of Fig. 5. In this view the wooden striking block is omitted.

The pile itself comprises a body of concrete of any desired shape in cross section and of any length required, together with a driving point of cast or wrought iron. In addition thereto there may be metallic reinforcements of any character. In the draw- 110

ings I have shown deformed bars reinforcing the concrete but it is to be understood that any form of reinforcement common to concrete constructions may be employed.

5 The pile 1 comprises a column of concrete 2 of any required length, and in the drawings this column is shown as rectangular in cross section although, as stated, this shape is not imperative.

10 The driving point 3 comprises a shell portion 4 inclosing the lower end of the concrete, and from this extends a flange 5. The lower portion of the member 3 is of pyramidal shape at 6, forming a point 7 for 15 piercing the earth through which the pile is driven. The interior of the driving point is more or less hollow before the pile is cast, so that the concrete enters the point and forms a homogeneous body of the pile 20 and point. The point is divided by means of cross webs 8, 9 of X formation. These webs make the driving point very strong so that it will stand the extreme pressures and they also form a convenient means for anchoring the reinforcing rods where such are 25 used.

The webs 8, 9 each have an aperture 10 and for each web there is a deformed reinforcing rod 11 having its lower end passed 30 through the aperture 10 of the web and bent back upon the rod, where it is fastened by a winding 12 of wire. These rods may extend upward to the top of the pile and they serve in well known manner to reinforce the concrete. 35

In addition to serving as reinforcements to the pile, these rods serve to transmit part of the driving force to the concrete of the pile. As the driving force is applied to the 40 driving point through the driving form and as these rods are anchored to the driving point tensile stresses are exerted through the rods and these stresses are transmitted through the rods to all parts of the concrete to overcome the resistance caused by the 45 partial earth friction on the pile.

The rods 11 may be held apart by spacing wires 13 wound around them at suitable intervals for the purpose of holding the rods in position while the pile is being cast. 50

The pile as described above, is cast in a suitable casting form above ground, so that the pile consists of a homogeneous body of concrete and a driving point. After the pile has been cast or poured of wet concrete in the casting form it may be allowed to stand for any desired length of time before it is driven in order that it may be thoroughly seasoned. The seasoning will, of course, improve the quality of the pile and avoid the development of subsequent weakness from subterranean moisture. 55

The driving form comprises, primarily, longitudinal members arranged lengthwise 60 of the pile and adapted to transmit the driv-

ing force to the driving point but not through the pile itself. That is, the shock of the driving is received by the driving form, so that the pile is relieved of at least the direct blow and is thus prevented from 70 being fractured during driving.

These longitudinal members are here shown as of angle or channel metal of commercial form, preferably of channel form. The channel bars 14, 15 are shown disposed 75 on opposite sides of the pile with their side webs 16 straddling the pile and with the outer faces of their main webs turned away from the pile.

I prefer to arrange plates 17 between the 80 webs 18 and the wall 4 of the driving point and resting on the flange 5. These plates tend to make the construction more rigid where the greater pressures occur and they also serve to space the members 14, 15 from 85 the concrete so that there will be little or no friction between these form bars and the pile when the bars are withdrawn.

I also prefer to provide plates 19 on the outside of the webs 18. The purpose of 90 these plates is to strengthen the form members 14, 15.

I have shown the members 14, 15 each made of a single piece of channel steel but it is to be understood that they may be built 95 up of several pieces secured together.

The channel bars 14, 15 and the plates 17, 19 may and preferably do, all rest upon the flange 5.

In addition to the above I have shown side 100 plates 21 riveted to the webs 16 of the channel bars.

On opposite sides of the driving point there are pairs of converging grooves 22. On the plates 21 there are projections 23 105 which slide in these grooves. When the pile is assembled in the driving form preparatory to driving, these projections 23 enter the grooves 22 and as they travel down the converging grooves the channel bars and 110 associated parts are drawn closely against the driving point member. On the other hand, when the form is withdrawn after the pile has been driven this connection causes the lower end of the form members to 115 separate and thus free themselves from the pile.

The construction of the head of the driving form is shown in Figs. 1, 5 and 6. It consists of a block 24 having a socket 25 at the top to receive a wooden impact block, 120 The block is within a frame consisting of the side plates 26 and channel bars 27, the guides 28 of the latter straddling the leads 29 of the pile driver and acting to guide the pile. There are preferably provided plates 125 30 lying outside the plates 19 and these and the bars 14, 15 are all bolted to the head block 24 by means of bolts 31. The head block is bolted to the members 26 by means of the bolts 32.

There are rods or shafts 33 which slide in opposite slots 34 in the frame members 26, there being one rod or shaft on each side of the head block 24. These rods or shafts 5 pass through the webs 16 of the channel bars and they are secured by means of heads 35 and nuts 36. On each side of the head block there is a pair of links comprising a link 37 having its upper end fulcrumed to one of the 10 rods 33 and a link 38 having its upper end fulcrumed to the other rod 33. The lower ends of these links are connected by a pin 39 which has an eye 40 to receive a hook on the tackle (not shown) of the pile driver.

15 As long as the bolts 32 and 31 are in place as shown in Figs. 5 and 6 the head construction is tightly held together and the force of the blows of the driver on the head is transmitted through the driving form. When it 20 is desired to place a pile in the form the bolts 31, 32 are removed and the tackle is connected with the eyes 40. Upon the tackle being drawn upwardly the links 37, 38 will be caused to spread and the rods 33 25 will travel out of the recesses 41 in the head block and they will travel along the slots 34 in the members 26.

Since these rods 33 are connected with the channel bars 14, 15 the latter will be separated 30 at the top sufficiently to allow a pile to be placed between them. It will be understood that the bolts 31, 32 are to be removed and the block 24 lifted off to permit the pile to enter the frame. After the pile 35 has been placed in the driving form the block 24 is replaced, the links are forced down to draw the form close against the block 24 and the bolts 31, 32 are replaced.

Fig. 1 shows the pile and form in position 40 for driving. The pile driver acts upon the head of the driving form and the force is transmitted through the channel bars 14, 15 and reinforcing plates 19 to the driving point 3, so that the downward force is not 45 applied directly to the concrete pile and it cannot, therefore, cause a fracture in the pile. The form may be driven through any material through which any pile can be driven.

50 There is more or less of a rebounding action to the pile and form. This is resisted more or less by the friction of the earth on the driving form and upon the pile, and in this respect it is to be noted that two sides 55 of the pile are in contact with the earth. To further prevent this rebounding action from injuriously straining the pile I have provided a block 42 which is secured between the form members by means of bolts 60 43. This block rests against the head of the pile so that any upward thrust is transmitted to the driving form and the pile is prevented from jumping in the form, from separating from the driving point, or from 65 otherwise being injured. It will be under-

stood that this block will be positioned on the form at the proper height to correspond with the position of the head of the pile.

The use of the device has been more or less set forth in the foregoing description. After 70 the pile has been placed in the form and both have been driven to the desired depth the block 24 is removed. The form is then withdrawn by suitable tackle. Upon the commencement of the upward movement of 75 the form the projections 23 will be guided by the grooves 22 in such manner that the form will be spread sufficiently to disengage it from the driving point. As the channel bars 14, 15 were held separated from 80 the pile during driving by the plates 17 there will be comparatively little resistance to the upward movement of the form. Since the form does not entirely surround the pile the latter will be held by earth friction and pressure from being drawn upwardly with the form when it is withdrawn. This insures the pile remaining at the lowest depth to which it had been driven, which 85 is an important feature. 90

It is to be understood that the driving point remains in the ground as a permanent part of the pile.

The form is used over and over, so that the only metal which has to be supplied is 95 that used for reinforcing (when reinforcement is employed) and the driving point.

In driving very deep it may be desirable to withdraw the form in sections. In that event the head is taken apart, the block 24 100 is removed and the channel bars 14, 15 are removed separately.

Having described my invention, what I claim is:

1. A device of the class described comprising a solid, precast concrete pile, a reinforcing member embedded in the pile and extending substantially throughout the length thereof, a driving point to which said reinforcing member is permanently and securely 110 anchored, and an exterior driving form adapted to receive the entire driving force and to transmit driving force to said driving point whereby the head of the pile is not subjected to any part of the concussion 115 of the driving force and whereby the entire concrete portion of the pile is pulled into the ground by the said driving point.

2. A device of the class described comprising a solid, precast, concrete pile, a reinforcing member embedded in the pile and extending substantially throughout the length thereof, a driving point to which said reinforcing member is permanently and rigidly anchored, said driving point being 120 of such size as to extend beyond the peripheral surface of the pile, an exterior driving form resting on the extended portion of said driving point, the driving point being 125 adapted to receive the driving force where- 130

by the entire concrete portion of the pile is pulled into the ground as an integral part of said driving point.

3. A device of the class described comprising a solid, precast, monolithic concrete pile, a reinforcing member embedded in the pile and extending substantially throughout the length thereof, a driving point to which said reinforcing member is permanently and rigidly anchored, and an exterior driving form disposed lengthwise of the pile and adapted to transmit driving force to said driving point, the driving force applied to said driving point being exerted substantially over the entire transverse cross section of the pile for substantially its full length by said reinforcing member to pull the solid pile into the ground as an integral part of said driving point.

20 4. A device of the class described comprising a solid, precast, concrete pile, metal reinforcing members embedded in the pile and extending substantially throughout the length thereof, a driving point to which said reinforcing members are permanently and securely anchored, and a driving form disposed lengthwise of and exterior of the pile and adapted to transmit driving force to a part of said driving point outside the peripheral surface of the pile, said driving form comprising separate members extending substantially the length of the pile and partly inclosing the outer peripheral surface of the pile whereby a portion of the earth friction which would otherwise be exerted upon the pile is caused to act upon the driving form, the driving force applied to said driving point being exerted substantially throughout the solid transverse cross section of the pile for substantially its full length to pull the entire concrete portion of the pile into the ground as an integral part of said driving point.

45 5. A device of the class described comprising a solid, precast monolithic concrete pile, metal reinforcing members embedded in the pile and extending substantially throughout the length thereof, a driving point to which said reinforcing members are permanently and rigidly anchored, and an exterior driving form disposed lengthwise of the pile and adapted to transmit driving force to said driving point, and comprising members adapted to be withdrawn separately after the pile has been driven, the driving force applied to said driving point being exerted substantially throughout the solid transverse cross section of the pile for substantially its entire length by said reinforcing members to pull the entire solid concrete portion of the pile into the ground as an integral part of said driving point.

60 6. A device of the class described, comprising a solid, precast monolithic concrete pile, metal reinforcing members embedded

in the pile and extending over the full length thereof, a driving point permanently secured to the pile by said reinforcing members, and an exterior driving form composed of separate driving members disposed lengthwise of the pile, extending beyond the head of the pile, and adapted to transmit driving energy to part of said driving point outside the peripheral surface of the pile and then to be separately or collectively withdrawn, the driving force applied to said driving point being exerted substantially throughout every part of the solid concrete portion of the pile by the reinforcing members to pull the complete pile into the ground without concussion upon the head of the pile from the driving force.

7. A device of the class described comprising a concrete pile, a driving point therefor, and a driving form composed of a plurality of longitudinally disposed metal members partially inclosing the pile whereby a portion of the earth friction which would otherwise be exerted upon the pile is caused to act upon the driving form, and means for detachably securing said form to said driving point, spacing members between said driving form and point whereby a substantial portion of the surface of said form is spaced from said pile to reduce the area of contact between the pile and driving form.

8. A device of the class described comprising a concrete pile, a driving point therefor, and a driving form arranged lengthwise of the pile and comprising separable members adapted to transmit the driving force to said driving point, and means for drawing said form members toward the driving point and adapted to release said members therefrom upon upward movement of the form members.

9. A device of the class described, comprising a concrete pile, a driving point therefor having a shoulder and converging grooves, and a driving form comprising members arranged lengthwise of the pile and adapted to rest on said shoulder and projections engaging said grooves whereby the form members will be drawn toward said driving point.

10. A device of the class described, comprising a concrete pile, a driving point therefor, and a driving form comprising channel bars arranged to partially surround said pile and to transmit the driving force to said driving point, means for drawing said channel bars toward said driving point and spacing members between the channel bars and driving point.

11. A device of the class described, comprising a concrete pile, a driving point therefor, and a driving form comprising channel bars arranged to partially surround said pile, and to transmit driving force to

the driving point and an abutment member connected between said channel bars and arranged to form an abutment against which the top of the pile may engage and adapted to prevent upward thrust of the pile relatively to the driving form.

12. A driving form for piles, comprising bars adapted to receive a pile between them, a frame movable between the leads of a pile driver, means engaging said bars and slid- 10 able laterally on said frame, for separating said bars.

13. A driving form for piles, comprising bars adapted to receive a pile between them, a frame slideable between the leads of a pile driver and provided with slots, a removable head block between said bars, bolts passing through said bars and engaging in said slots and converging links connected with said bolts for spreading said bars. 20

Signed at the city, county and State of New York, this 25th day of August, 1915.

CLARENCE S. HOWELL.
